UNITED STATES PATENT OFFICE.

SARAH M. WILCOX, OF FAIRMOUNT, ILLINOIS.

SPOOL-HOLDER.

1,189,415.

Specification of Letters Patent.

Patented July 4, 1916.

Application filed August 11, 1914. Serial No. 856,292.

To all whom it may concern:

Be it known that I, SARAH M. WILCOX, a citizen of the United States, residing at Fairmount, in the county of Vermilion and 5 State of Illinois, have invented certain new and useful Improvements in Spool-Holders, of which the following is a specification.

This invention relates to spool holders, and is particularly adapted for use in crocheting when it is desired to move from 10 place to place and always carry a crocheting spool.

The object of this invention is to provide a spool holder that can be applied to a table, 15 window sill or any type support and can be easily and quickly taken from the same.

A still further object of this invention is to provide a spool holder that comprises substantially a pivoted spring clip having 20 mounted thereon a spindle that is adapted to be passed through the bore formed in an ordinary spool.

It is a further object of this invention to provide a spool holder as described with 25 means whereby when the same is in engagement with a support, no metallic parts of the same that would mar the support can come in contact therewith.

A still further object of this invention is 30 to provide a device of the kind above described, that is simple in construction, efficient in operation, consists of the minimum number of parts, and thereby can be manufactured for the minimum amount.

With these and other objects in view, this 35 invention consists of certain novel constructions, combinations and arrangement of parts as will be hereinafter fully described and claimed.

In the accompanying drawings:—Figure 40 1 is a view in elevation of the improved device mounted upon a support. Fig. 2 is a top plan view of the device mounted upon a support. Fig. 3 is a section taken on line 45 3—3 of Fig. 2.

Referring to the parts by reference numerals, the device comprises essentially a pair of members 10 and 11 having outwardly turned ends 12 that are adapted to 50 be used for finger-engaging means to operate the same. A plurality of ears 13 are bent intermediate the length of the members 10 and 11 at the marginal edge thereof, said ears 13 of the section 10 being placed 55 on the outside of said ears formed on the

section 11, and inasmuch as the same have alined openings, a pin or like means 14 is passed therethrough to pivotally mount the sections or members 10 and 11. At the opposite end of the members or sections 10 and 11 from that of the outwardly turned finger-engaging portions 12, is a circular portion 15.

The circular portion 15 formed on one end of the member or section 10 is provided with a threaded opening formed centrally thereof, and extending from the lower edge of said opening is a collar 16 that is also internally threaded so as to provide a threaded opening of greater length than the thickness of the member 10. A hollow spindle 17 having one end of the same externally threaded and being threaded into the threaded opening in the member 10 is thus substantially secured thereto. The opposite end of the spindle 17 from that of its engagement with the section or member 10 is internally threaded, and a cap 18 having an externally threaded projection 19 is positioned on the end of the spindle 17 by means of the projection 19 in threaded engagement with the end of the spindle. It is, of course, obvious that a spool is mounted on the spindle passing through the bore formed in the spool, and after the same is thus placed, the cap 18 is positioned and the spool cannot be taken from the spindle, inasmuch as the cap 18 is of greater diameter than the ordinary bore of a crochet or other spool. When this device is used for sewing or other uses than crocheting, needles can be placed in the tubular spindle 17, and thus the same will accomplish the dual function of rotatably mounting the spool and receiving the needles as set forth.

Secured on the inner faces of the circular portions 15 of the sections 10 and 11, are pads of felt, rubber or the like 20, so as when the device is in engagement with a support as shown in the accompanying drawings, the support, if it happens to be a highly polished piece of furniture, will not be marred in any way by the placing of the spool holder thereon. To insure a positive gripping of the device upon a support, inwardly directed pins 21 are carried by the sections 10 and 11, and a coil spring 22 has its ends positioned over the spring, and is thereby held in engagement with the inner faces of the sections 10 and 11, thereby nor-

mally exerting a pressure upon the same that will cause the circular portions 15 of the sections to come toward each other.

It will be seen from the foregoing description that a simple spool holder has been provided that can be carried from place to place, and means have been provided on the spool holder whereby there is absolutely no likelihood of a spool held thereby from becoming disengaged therefrom. The device will be very cheap to manufacture, inasmuch as the sections 10 and 11 are formed each from a blank sheet of metal, and thus can be made cheaply and quickly.

It is obvious that minor changes may be made in the form and construction of this invention without departing from the material parts thereof. It is therefore not wished to confine the invention to the exact form herein shown and described, but it is wished to include all such as properly come within the scope claimed.

I claim—

1. A spool and needle holder including the combination with a clip forming a flange of the spool holder, of a hollow needle receiving spindle interiorly threaded at one end and a threaded closure member for said spindle and carrying a flange coacting with said clip to restrict movement of a spool on said spindle.

2. A spool and needle holder including the combination with a clip forming a flange of the spool holder, of a hollow needle receiving spindle accommodating the spool and open at one end, and a closure for said open end adapted to retain the spool in place on the spindle and to hold the needles in the said spindle.

In testimony whereof I affix my signature in presence of two witnesses.

SARAH M. WILCOX.
